UNITED STATES PATENT OFFICE.

WILLIAM F. THOMPSON, OF SPRINGFIELD, MISSOURI, ASSIGNOR OF ONE-HALF TO
WILLIAM C. LOHMEYER, OF SPRINGFIELD, MISSOURI.

SELF-CALCULATING SCALE.

1,095,246.

Specification of Letters Patent.

Patented May 5, 1914.

Application filed April 5, 1913. Serial No. 759,124.

To all whom it may concern:

Be it known that I, WILLIAM F. THOMPSON, a citizen of the United States, residing at Springfield, in the county of Greene and State of Missouri, have invented certain new and useful Improvements in Self-Calculating Scales, of which the following is a specification, reference being had to the accompanying drawings.

10 This invention comprehends certain new and useful improvements in calculating instruments and has for its primary object to provide a device of this character which will be of extremely simple construction and highly efficient in use.

Another object is to provide a scale of this character which will be especially adapted for use by machinists in setting valves on locomotives or other steam engines.

20 Another object is to provide an instrument of this character by means of which the workman may readily determine the change necessary to an eccentric blade of a valve to properly adjust the valve rod.

25 Another object is to provide a device of this character by means of which the workman may readily determine the change necessary to the off-set of the eccentric block when adjusting the valves of steam engines and the like.

30 A further object is to provide a calculating scale of this character by means of which the degree of changes necessary may be readily calculated by simply moving the pivoted indicator beam and securing the same in adjusted position, said indicator beam having a beveled edge crossing graduated lines upon the face of the scale and the beam also being provided with an indicating point engaged 35 with a graduated curved or arcuate line at one end of the scale or plate.

35 A further object is to provide a calculating scale of this type which will be of extremely simple construction and operation and highly efficient and accurate in use.

45 With the above and other objects in view, this invention consists in the novel features of construction, combination and arrangement of parts to be hereinafter more fully 50 described, claimed and illustrated in the accompanying drawings, in which—

Figure 1, is a plan view of my improved calculating instrument. Fig. 2, is an end view, looking at the lower end of the tool. Fig. 3, is a similar view looking at the upper

end of the tool. Fig. 4, is an enlarged detail view to show more correctly the markings upon the plate, the central portion of the tool being broken away and the ends brought closer together. Fig. 5, is a detail view of the beam pivoting member removed. Fig. 6, is a detail view of the thumb-screw removed.

Referring more specifically to the drawings in which similar reference characters 65 designate corresponding parts throughout the several views, 1 designates the plate which is of rectangular form in general outline and preferably formed of a thin durable material and may be of any preferred dimensions but is preferably about two inches wide and fifteen inches long, the purpose of which will presently appear. The plate is provided upon one face with a longitudinal line 2 about one-fourth of an inch inwardly 70 of the left edge of said plate and transverse lines 3 are also provided one-half an inch apart, the lines indicating the inches extending clearly across the plate and the lines indicating the half inches extending only half 75 the distance between the longitudinal line 2 and the opposite edge of the plate. The transverse lines 3 are graduated to indicate one-thirty-second inches and one-sixty-fourth inches, as shown at 4. The plate 1 is 80 graduated along its left edge to indicate one-eighth inches between the inch indicating lines 3, as shown at 5 while suitable markings 6 are provided along the opposite edge of the plate to indicate one-sixteenth inches. 85

The indicator beam 7 is pivoted at its lower end to the front or graduated face of the plate 1, by means of the pivot pin 8 which extends through the lower end of the beam and has a slightly reduced threaded 90 portion 9 threaded through the plate 1, adjacent the lower end of said plate and slightly inwardly of the longitudinal line 2. The indicator beam 7 is formed of any suitable thin material and has a beveled edge 10 and 95 when the indicator beam is in one position, the beveled edge 10 thereof is engaged against the longitudinal line 2 and the edge of the indicator beam is therefore parallel with the adjacent or left edge of the plate 1. 100

Adjacent the opposite or upper end of the plate 1 and preferably above the transverse line 3 indicating the fourteenth inch of the scale, I have provided a curved or arcuate slot 11 which extends across the 110

plate and has one end terminating adjacent the longitudinal line 2 while the opposite end is located adjacent the opposite edge of the plate. A curved or arcuate line 12 is 5 provided above the slot 11 and spaced from the same, said line extending in curvature of the slot 11 and having the graduation marks 13 positioned along said line to indicate the degrees of circle, the purpose of 10 which will presently appear. The thumb-screw 14 extends through the slot 11 from the rear face of the plate and has its threaded portion 15 engaged in the upper end of the indicator beam 7 extending across the 15 slot 11. The thumb-screw 14 serves as means to move the indicator beam and secure the same in adjusted position with the extended indicating point 16 of the beam 7 pointing to the proper graduation mark 13, 20 by tightening the thumb-screw 14 and thereby binding the upper or free end of the indicator beam against the front face of the plate 1. It will be understood that the indicating point 16 is formed by extending 25 the beveled or front edge 10 of the indicator beam 6 beyond the remaining portion of the upper or free end of said beam.

In use, when employing the instrument or scale to ascertain the change necessary to 30 the eccentric blade of a locomotive or other valve and the change shown on valve rod is seven-thirty-seconds inch and assuming that the top rocker arm is 12 inches long and the bottom arm ten and a half inches long, I. 35 first loosen the thumb-screw 14. I then move the beam 7 over to the right just seven-thirty-seconds inch on the twelve inch line on the plate 1 and again tighten the thumb-screw 14. By looking at the ten and a half 40 inch line on scale, the change necessary to the eccentric blade may be readily seen. When employing the scale to determine the proper off-set of the eccentric key when there is a change of three-thirty-seconds 45 inch (for example) in the lead on the eccentric block, as shown on valve rod, assum-

ing the radius of the valve travel is two and one-half inches and the radius of the journal is four inches, I simply loosen the thumb-screw 14 and move the indicator beam over three-thirty-seconds on the two and a half inch line on the scale. The proper off-set for the eccentric key is then indicated by the four inch line. It will be seen that by employing this scale, much time 55 and labor is saved. It will be understood that this calculating scale may be employed in many other and similar cases and will be accurate and efficient in use.

While I have shown the preferred embodiment of my invention, it will be understood that minor changes in the details of construction may be made within the scope of the appended claim, without departing 60 from the spirit of my invention.

Having thus described my invention, what I claim is:—

A device of the class described comprising a rectangular plate provided with an opening adjacent one corner and a transversely extending arcuate slot adjacent the opposite end of said plate, in combination with an indicator beam having one face beveled and extended at one end to form an indicator point, said plate having a scale upon 70 one longitudinal edge and transverse scales extending across one face from the scale upon said longitudinal edge, the transverse scales being spaced apart, a pivot member carried by one end of the indicator beam 75 and secured in said opening, and a combined guide and locking member carried by the opposite end of the beam and engaged through said slot of the plate for guiding the beam and securing the same in adjusted 80 position upon the plate.

In testimony whereof I hereunto affix my signature in the presence of two witnesses.

WILLIAM F. THOMPSON.
